Fig. 3

Fig. 4

Fig. 5

FIGURE 1 is a perspective view of a display shelving unit embodying my new design; the broken line representation of a second unit being for purposes of illustration only;

FIGURE 2 is a front elevational view thereof;

FIGURE 3 is a top plan view thereof;

FIGURE 4 is an elevational view taken from one side thereof; and

FIGURE 5 is an elevational view taken from the side opposite that shown in FIG. 4.

The dominant features of the design reside in the portions shown in full lines.

I claim:

The ornamental design for a display shelving unit, as shown and described.
